UNITED STATES PATENT OFFICE.

HUBERT K. KRANTZ, OF BROOKLYN, NEW YORK, ASSIGNOR TO WESTINGHOUSE ELECTRIC & MANUFACTURING COMPANY, A CORPORATION OF PENNSYLVANIA.

SNAP SWITCH.

Application filed September 24, 1920. Serial No. 412,468.

To all whom it may concern:

Be it known that I, HUBERT K. KRANTZ, a citizen of the United States, and a resident of Brooklyn, in the county of Kings and State of New York, have invented a new and useful Improvement in Snap Switches, of which the following is a specification.

My invention relates to electric snap switches, and it has for its object the provision of a construction whereby a positive starting movement may be imparted to the switch blades and the movement thereof then completed by a spring.

In snap switches, it sometimes happens that the blades stick slightly in one of the extreme positions and will not move readily, under the spring tension alone. To overcome this objection, I provide a simple means whereby movement of the switch handle by the operator, in addition to creating spring tension, also imparts positive starting movement to the switch blades. A form of device embodying this feature is shown in the accompanying drawing, where-in—

Figure 1 is a plan view of a switch embodying my invention;

Fig. 2 is an elevational view, with a portion of the switch frame removed; and

Fig. 3 is an elevational view taken at right angles to that of Fig. 1.

My invention is shown as applied to a switch of the oscillating type having the usual base 3, two pairs of contact members 4 and a switch frame 5.

A handle 6, is secured by a screw 6^a to a member of inverted U-shape that has projections 8 and 9 and is pivoted at 7. The projections 8 and 9 alternately abut against opposite edges of a blade arm 10, as the switch handle is moved to open and to close the switch.

A pair of blades 12 are pivoted, at 11, to the frame 5 and are rigidly connected to the arm 10. These blades are adapted to move into and out of engagement with the contact members 4 in the usual manner.

A tension spring 13, with its opposite ends connecting the blade arm to the handle, as shown, is provided and serves to impart the necessary snap movement to the blades.

If, with the switch in open position as shown in Fig. 2, the handle is moved to the right, it will carry with it the upper

end of the spring 13, thereby increasing the tension on such spring and changing the angularity of the line of pull exerted on the blade arm. During this movement of the handle, the projection 8 is brought to bear against the blade arm and thus imparts initial movement to the blade. The spring then completes the movement of the blades to closed position.

To open the switch, the movement of the parts in the operation just described is reversed, and the projection 9 of the handle is brought to bear against the blade arm to impart positive movement to the blades and move them out of frictional engagement with the contact members 4.

Various modifications might be made without avoiding the essential features of the invention. For instance, the spring might be under a constant tension and need not necessarily have such tension increased by movement of the handle; the movement of the handle serving simply to change the angularity of the spring with respect to the blade arm and to impart positive starting movement to the blades.

I claim as my invention:—

1. The combination in an electric switch, of a frame, a contact carrier of U-shape pivotally supported on the frame, an operating lever pivotally supported on the frame at a point above the support for the carrier, spaced lugs carried by the lever and disposed at opposite sides of the carrier to effect a lost-motion connection between the lever and the carrier, and a yielding connection between the lever and the carrier, said yielding connection being secured to the lever at a point eccentric of its pivotal support.

2. The combination, in an electric switch, of a frame of U-shape, a contact carrier of U-shape pivotally supported on said frame, an operating lever of inverted U-shape pivotally supported on said frame at a point above the support for the carrier, spaced lugs carried at the extremities of said lever, the lugs at each extremity being disposed at opposite sides of the carrier to effect a lost-motion connection between the lever and the contact carrier, and means for yieldingly connecting the lever to the carrier, said connecting means being secured to the lever at a point eccentric of its pivotal support.

3. In a switch structure, a frame of U-

shape, a contact carrier of U-shape pivotally mounted in said frame, an operating lever of inverted U-shape pivotally mounted adjacent to the open portion of said frame, and between the legs thereof, the legs of said operating lever having means for providing a lost-motion connec-

tion to said contact carrier and for directly engaging and positively actuating the said carrier.

In testimony whereof, I have hereunto subscribed my name this 17th day of September 1920.

HUBERT K. KRANTZ.
